DESIGN FOR A HEAT RETAINING NURSING BOTTLE HOLDER

Charles N. Lockwood, Chicago, Ill.

Application July 18, 1940, Serial No. 93,774

Term of patent 7 years

To all whom it may concern:

Be it known that I, Charles N. Lockwood, a citizen of the United States of America, residing at 2061 Southport Avenue, Chicago, Illinois, have invented a new, original, and ornamental Design for a Heat Retaining Nursing Bottle Holder, of which the following is a specification, reference being had to the accompanying drawing forming a part thereof.

Fig. 1 is a perspective view of a heat retaining nursing bottle holder showing my new design; Fig. 2 is a front elevation, Fig. 3 a rear elevation and Fig. 4 a side elevation of the same on a reduced scale.

I claim:

The ornamental design for a heat retaining nursing bottle holder, substantially as shown.

CHARLES N. LOCKWOOD.
